UNITED STATES PATENT OFFICE.

WILLIAM WESTPHAL, OF LOS ANGELES, CALIFORNIA.

COMBINED DAVENPORT AND BED.

Application filed April 18, 1922. Serial No. 555,015.

To all whom it may concern:

Be it known that I, WILLIAM WESTPHAL, a citizen of the United States, residing at Los Angeles, in the county of Los Angeles and State of California, have invented a new and useful Combined Davenport and Bed, of which the following is a specification.

An object of this invention is to provide furniture of the davenport bed type which will give a longer bed surface when in bed position than has heretofore been provided for davenport beds having the same overall length.

An object of this invention is to provide means whereby a davenport bed having a seat length corresponding to the width of a full size bed will, when adjusted to bed forming position, present a bed surface having a length corresponding to the length of a full size bed.

An object is to provide simple and efficient connecting means between the seat and back frames of a davenport bed.

An object is to provide a davenport bed that can be opened and closed with minimum effort.

Other objects, advantages and features of invention may appear from the accompanying drawings, the subjoined detail description and the appended claims.

The accompanying drawings illustrate the invention.

Figure 1 is a front elevation of a davenport bed constructed in accordance with this invention.

Fig. 2 is an end view of the davenport bed shown in Fig. 1.

Fig. 3 is a section on plane indicated at w^3 , Fig. 1, of the device when extended in bed form.

Fig. 4 is a plan of the frame of the davenport shown in Fig. 1 in seat form. The upholstering and springs being removed.

Fig. 5 is a plan of the frame open as in Fig. 3 with mattress in place.

Fig. 6 is a fragmental transverse section of one of the arms, showing the pillow receptacle.

Fig. 7 is a transverse section of the frame in seat position.

Fig. 8 is a transverse section of the frame. Full lines indicate a position of parts while being moved into bed form, or vice versa,

and dotted lines indicate the position of the parts in bed form.

Fig. 9 is an enlarged fragmental edge view of the arm support.

Fig. 10 is a fragmental section on line x^{10} , Fig. 9.

Fig. 11 is a fragmental enlarged detail of the top rail and a portion of its closing mechanism.

Fig. 12 is a fragmental section on line x^{12} , Fig. 8, showing the sliding connection between the reversible seat frame and the arm support.

Fig. 13 is a fragmental detail showing the lower end of the top rail closing mechanism.

The invention comprises a pivotally mounted reversible back frame 1; a pivotally mounted reversible seat frame 2; and pivotally mounted reversible arms 3, 4; said frames being mounted and connected together to turn simultaneously and so arranged to engage and turn said arms to change the device from bed form into seat form and vice versa; there being means connecting the lower ends of the back frame with the seat frame to cause the one to turn with the other from seat form to bed form and vice versa; there also being means to cause the arms to move simultaneously during changing of the device from bed form into seat form and vice versa.

As a support for the back-frame 1 and seat frame 2 there is provided a base 5 having a box-like chamber 6 that is bounded by a front piece 7, and pieces 8 and a floor 9.

The convertible back and bed bottom frame 1 is hinged by hinges 10 to the tops 90 and rear edges of the end pieces 8; and said frame 1 is provided with a seat-back cushion 11 on one side and a section of bed springs 12 on the other side. The convertible seat and bed bottom frame 2 is hinged at one edge by hinges 13 to the front piece 7 of the base 5 and is provided with a section of bed springs 14 and a section of seat springs 15 which latter are adapted to support the loose seat cushions 16.

It is thus seen that the reversible back frame is hinged by hinges 10 to one side of the base 5 and the reversible seat frame 2 is hinged by hinges 13 to the other side of the base at a lower level than that at which the back frame is hinged. The seat frame 2,

with its seat and bed springs, is adapted to extend horizontally between the arms 3, 4 at a lower level than said arms and upon the inside of the front piece 7 when the device is in seat form; and the end pieces 5 of said frame 2 are adapted to rest upon the end pieces 8 of the base 5 when the device is in seat form.

The free edge 2'' of the seat frame 2 is 10 provided with a flexible loop 17 for use in opening and closing the bed.

Connecting links 18 disposed at each end of the seat frame are pivotally connected below the seat level, to the back frame as at 19 15 and to a projecting arm 20 of the seat frame, as at 21; so that the seat and back frames are connected together with a single connecting link at each end of said frames.

When the parts are in closed or seat position, the space 22 formed between the back frame 1 and the rear wall 23 of the davenport is closed at the top by a top rail 24 extending across between side wings 25, 26, that are fixed to the end pieces 8 and the rear wall 23. Said side wings 25, 26 may be upholstered or otherwise finished and are adapted to continue forwardly and outwardly adjacent to the end pieces 8 of the base 5. Said wings 25, 26 close the ends of 30 the open space between the back frame and the back wall when the parts are in seat position.

The arms 3, 4 comprise arm bases 27, 28 and reversible supports 29 which may be upholstered or otherwise finished on their upper surfaces when in seat position. Said supports 29 are hinged by hinges 30 to the front edges of the arm bases formed by the side members 31, 32 which are secured to the 40 end pieces 8 and form an upward extension of the base 5. The arm bases are closed at their front and rear ends in any well known way. The floor 9 closes the lower part of the arm bases.

45 Covers 33 are hinged to the side members 31 and there is thus formed in each arm 3 and 4 a closed receptacle 34 that is adapted for various uses, such as receiving a pillow 35 or the like. Wire extensions 36 are pivotally connected to the cover 33 and reversible support 29 by any well known means such as staples 37.

Means are provided whereby the reversible arm supports 29 are automatically moved to 50 bed position when the seat and back frames are moved into bed form, and comprise rollers 38 mounted on bearings or bolts 39 secured to the ends of the reversible seat frame 2, and are adapted to engage cooperating 55 means, on the reversible support 29, which comprise a sheet of metal bent to form a guide way 40 fixed to the arm supports 29 by suitable means as the screws 41; and a pivoted guide 42 weighted at one end as at 43 60 and at 44 pivoted to the arm support 29. A

standard 45 is pivoted at 46 to the arm support 29 and is provided with an extension 46' that is adapted to support the outer end of the reversible seat frame 2 when the parts are in bed position.

Means are provided whereby the top rail 24 is automatically opened and closed when the parts are moved from seat to bed form and vice versa, and said means comprise a rod 47 mounted for longitudinal movement 75 in the guide way 48 and provided at its upper end with a roller 49 which is adapted to engage the rear wall of the top rail 24. The rod 47 is connected at its lower end to one end of the top rail operating lever 50 which is pivoted at 51 to a frame member 52 of the back wall 23. The lower end of the reversible back-frame 1 is adapted to move the free end of the lever 50 downwardly so as to move the roller 49 upwardly.

When the parts are in seat position as shown in Fig. 7 the reversible back-frame 1 holds the free end of the lever 50 down so as to hold the roller 49 against the rear edge of the top rail 24, and thereby holds such rail in closed position. When the parts are moved from closed to open position, the back frame 1 releases the lever 50 and the spring 52' mounted between the bearing 48 and the collar 53 which is secured to the rod 47 by 90 means of pin 54 and will force the rod 47 downwardly so as to disengage the roller 49 from the rear edge of the top rail 24. A spring 55 fixed by screws 56 to the top of rear wall 23 (see Fig. 11) is interposed between the top of said wall 23 and the underside of the top rail 24 and operates to force the top rail upward so as to allow free movement of the back-frame 1 when the parts are moved into open position.

A brace 57 is secured at one end to the end wall 8 of the base 5 and is provided at its other end with an extension 58 which is adapted to engage the reversible back-frame 1 when the parts are moved into bed form. A spring 59 is secured at one end to the floor 9 of the base 5 and is secured at its other end to the back-frame 1 and is adapted to ease the seat and back frames into seat and bed form.

110 In Fig. 5, a mattress 60 is shown secured to each of the frames 1, 2 or springs 12 and 14, and is adapted to separate at a when the parts are moved to seat position. The retaining straps 61 may be used to retain the wings 62 that are hinged to the mattress 60 and bed clothes, not shown, in position on the seat frame when the parts are in seat form. The wings 62 are adapted to be turned outward as shown in dotted lines. Said wings rest upon their cooperating supports one of which is formed by the cover 33 and wire 36 and the other by the arm support 29 and wire 36'.

115 120 125 130 To move the parts from seat to bed form,

the loose seat cushions 16 are first removed and the seat frame 2 may be easily raised by pulling up the flexible tab 17. As the seat frame is moved upward and outward the 5 roller 38 engages the pivoted guide 42 and raises the reversible support 29.

This movement of the frame 2 causes the connecting link 18 to move the back-frame 1 forward on its hinges 10, and when the 10 back-frame is moved a sufficient distance forward, the lever 50 is released so as to allow the spring 52' to move the roller 49 out of engagement with the top rail 24, whereupon the spring 55 moves said rail upwardly into 15 the position shown in Figs. 3, 8 and 11. As the seat frame continues to move forward, the roller 38 enters the guide way 40 and supports the reversible arm support 29.

When the parts are moved a sufficient distance forward the weighted end 43 of the 20 guide 42 causes the light end of said guide to engage one rail 40' of the guide way 40 and thus causes the roller 38 to leave the way 40 by means of the opening 41'. The 25 support 45 assumes the position shown in dotted lines Fig. 8 by reason of gravity and as the parts are finally brought into full open position the seat frame 2 will be supported at its outer end by the extension 46'. 30 The wires 36 are then extended into the full line position shown in Fig. 5. The wings 62 of the mattress are then extended so as to be supported by the wires 36, arm supports 29, and covers 33 thus affording a longer 35 bed than is common to davenports having a length corresponding to the width of a full sized bed.

When it is desired to turn from bed form back into seat form the operation just described is reversed.

It is understood that various forms of means adapted to engage the reversibly mounted arms may be provided to cause the arms to be moved outward, and this invention is broadly new, basic and pioneer in that there is connected to the seat frame, means that are adapted to automatically turn the arms into extended position whereby the same are utilized as a bed bottom when the 50 parts are moved into bed form.

I claim:

1. In furniture of the character described; a base; a reversible back frame pivotally connected to said base at one side thereof; a reversible seat frame pivotally connected to said base at the other side thereof and at a level lower than that at which the back frame is pivoted; arms fixed to and projecting from the base and a link at each end of said seat and back frames pivotally connected at one end to said seat frame and at its other end to said back frame, said links being below the level of the seat frame when the frames are in seat form and adapted to simultaneously

turn said back frame with said seat frame.

2. In furniture of the character described, a base; a reversible seat frame pivotally connected to said base; a reversible back frame pivotally connected to said base; a link at each end of and pivotally connected to said seat frame and back frame, said links being below the level of the seat frame when the frames are in seat position and adapted for simultaneous turning of said frames on their pivots; arm bases at the ends of said base; and reversible arms pivotally mounted on said arm bases and adapted to cooperate with the seat frame to form a part of the bed surface when the furniture is opened out.

3. In furniture of the character described, a base; a reversible seat frame pivotally connected to said base; a reversible back frame pivotally connected to said base; arm bases at the ends of said base; and reversible arms pivotally mounted on said arm bases and adapted to cooperate with the seat frame to form a part of the bed surface when the furniture is opened out.

4. In furniture of the character described, a base; a reversible back frame pivotally connected to said base; a reversible seat frame pivotally connected to said base; means connecting said seat frame and back frame together for simultaneous turning of said frames on their pivots; arm bases at each end of said base; reversible arms pivotally mounted on said arm bases; and means on said seat frame adapted to engage said reversible arms to automatically move said arms on their pivots from normal position to reversed extended position and vice versa.

5. In a davenport of the character described, a base; a reversible back frame pivoted to said base; a reversible seat frame pivoted to said base; a link at each end of said frame pivotally connecting said back and seat frames together, said links being below the level of the seat frame when the frames are in seat form; arm bases at the ends of said base; arm supports pivotally connected to said arm bases; and means whereby said arm supports are automatically moved on their pivots to cooperate with said seat frame to form a bed surface when the seat frame is moved to bed position.

6. In a davenport of the character described, a base; a reversible back frame pivoted to said base; a reversible seat frame pivoted to said base; arm bases at the ends of said base; arm supports pivotally connected to said arm bases; and means whereby said arm supports are automatically moved on their pivots to cooperate with said seat frame to form a bed surface when the seat frame is moved to bed position.

7. In a davenport of the character described, a base; a reversible back frame pivoted to said base; a reversible seat frame pivoted to said base; means pivotally connecting said back and seat frames together; arm bases at the ends of said base and forming an upward extension thereto; arm supports pivotally connected to said arm bases; means whereby said arm supports are automatically moved on their pivots to cooperate with said seat frame to form a bed surface when the seat frame is moved to bed position; and means pivoted to said arm supports and adapted to be extended so as to 10 lengthen the bed surface.

8. In a davenport of the character described, a base; a seat frame pivoted to said base; a back frame pivoted to said base; arm bases at the ends of said base and comprising side members closed at their ends, arm supports pivotally connected to said arm bases; covers hinged to said side members and adapted to form a part of the bed surface when the frames are moved to bed 20 position; and means whereby said arm supports are moved on their pivots for the purpose specified when the seat and back frames are moved from seat to bed position, and vice versa.

9. In a davenport of the character described, a base; a seat frame pivoted to said base; a back frame pivoted to said base; means connecting said back and seat frames together for simultaneously turning said

30 frames on their pivots; arm bases secured to said base; reversible arm supports pivotally mounted on said arm bases; means connected to said seat frame and adapted to engage said arms to automatically move the arms on their pivots for the purpose specified; and means pivoted to said arm supports and adapted to be extended to lengthen the bed surface.

10. In a davenport of the character described having a back wall and a base; a seat frame pivoted to said base; a back frame pivoted to said base; means connecting said back frame and seat frames together for simultaneously moving said frames on their 40 pivots; a top rail adapted to close the space between the upper edge of the back frame and the back wall when the parts are in seat position; and means whereby said top rail is automatically raised when the parts are moved to bed position, and automatically lowered when the parts are moved into seat position.

11. In a davenport of the character described, a base; a seat frame pivoted to said base; a back frame pivoted to said base; means connecting said back and seat frames together for simultaneously turning said frames on their pivots; arm bases secured to said base; reversible arm supports pivotally 50 mounted on said arm bases; means secured

to said arm supports having a guide-way and a pivoted guide; and means secured to said seat frame adapted to be guided into and out of said guide-way by said pivoted guide and to move said arm supports into 70 bed position and seat position, corresponding to the position of the seat frame.

12. In a davenport of the character described, a base; a seat frame pivoted to said base; a back frame pivoted to said base; means connecting said back and seat frames together for simultaneously moving said frames on their pivots; arm bases secured to said base; reversible arm supports pivotally mounted on said arm bases; means secured to said arm supports having a guide-way and a pivoted guide; a roller fixed to said seat frame and adapted to be guided into and out of said guide-way by said guide; said roller being adapted to move said arm supports on their pivots, said arm supports being adapted to be utilized as a bed surface when in extended position.

13. In furniture of the character described, a base; a reversible back frame pivotally connected to said base; a reversible seat frame pivotally connected to said base; arm bases at each end of said base; reversible arms pivotally mounted on said arm bases; and means connected to said seat frame to move said arms on their pivots from normal position to reversed extended position when the seat frame is moved from seat position to bed position.

14. In furniture of the character described, a base; a seat frame pivoted to said base; a back frame pivoted to said base; arm bases at the ends of said base and comprising side members closed at their ends; arm supports pivotally connected to said arm bases; covers hinged to said side members and adapted to cooperate with said back frame to form a bed surface when said back frame is moved to bed position; means connected to said seat frame to move said arm supports on their pivots to cooperate with said seat frame to form a bed surface when the seat frame is moved to bed position; means pivoted to said arm supports and adapted to be extended so as to lengthen the bed surface; and means pivoted to said covers and adapted to be extended so as to lengthen the bed surface.

15. In a davenport of the character described, a base; a seat frame pivoted to said base; a back frame pivoted to said base; arm bases at the ends of said base; arm supports pivotally connected to said arm bases; means connected to said seat frame to move said arms on their pivots from normal position to reversed extended position when the seat frame is moved from seat position to bed position; and means pivotally connected to said arm supports and adapted to support said arm supports and the outer end of said

seat frame when the frames are moved to bed position.

16. In a davenport of the character described, a base; a seat frame pivoted to said base; a back frame pivoted to said base; projecting arms fixed to each end of said seat frame; and a link at each end of said frames being pivoted at one end to said projecting arms and at its other end to said back frame, 10 said links being below the level of the seat

frame when the frames are in seat form and adapted to simultaneously turn said back frame with said seat frame.

In testimony whereof, I have hereunto set my hand at Los Angeles, California, this 15 13th day of April, 1922.

WILLIAM WESTPHAL.

Witness:

ARTHUR F. LARRABEE.
